Edgar Gates & Co.

UNITED STATES PATENT OFFICE.

JACOB BELASCO, OF NEW YORK, AND ABRAHAM SHAPIRO, OF BROOKLYN, NEW YORK.

GARMENT-HANGER.

1,248,602.

Specification of Letters Patent. Patented Dec. 4, 1917.

Application filed July 22, 1916. Serial No. 110,635.

To all whom it may concern:

Be it known that we, JACOB BELASCO and ABRAHAM SHAPIRO, citizens of the United States, and residing respectively, at Bronx, 5 in the county of Bronx and State of New York, and Brooklyn, in the county of Kings, State of New York, have invented certain new and useful Improvements in Garment-Hangers, of which the following is a specification, such as will enable those skilled in 10 the art to which it appertains to make and use the same.

This invention relates to what are known as garment hangers and particularly to devices of this class designed for suspending an entire suit, or a plurality of separate garments; and the object of the invention is to provide an improved device of this 15 class composed of separate parts foldably connected and adapted to be folded compactly together to facilitate packing, shipping or similar operations, and with this and other objects in view the invention consists in a device of the class specified, 20 constructed as hereinafter described and claimed.

The invention is fully disclosed in the following specification, of which the accompanying drawing forms a part, in which the 25 separate parts of our improvement are designated by suitable reference characters in each of the views, and in which:—

Figure 1 is a side view of our improved garment hanger ready for use;

Fig. 2 a side view showing the parts of the hanger folded together and with a part of the construction broken away;

Fig. 3 a sectional view on the line 3—3 of Fig. 1;

Fig. 4 a sectional view on the line 4—4 of Fig. 2; and,

Fig. 5 a transverse sectional view on the line 5—5 of Fig. 2.

In the practice of our invention, we provide a device of the class specified, comprising the usual top yoke-shaped portion a composed of two parts a^2 hinged together at a^3 and adapted to be folded compactly together as shown in Fig. 2, and the lower or outer parts or ends of the separate parts a^2 are connected by a transverse brace member b composed of separate parts b^2 hinged together at b^3 .

Our improved garment hanger is preferably composed of sheet metal, and the separate parts a^2 of the top portion a are pref-

erably U-shaped in form, as clearly shown in Figs. 3 and 5, and the adjacent ends of said separate parts where they are hinged together overlap, as indicated in Figs. 1 and 60 2, and mounted between the separate parts thereof where they are hinged together at a^3 is a hat suspending device c , the free end portions of which are bent to form spring members c^2 between which the rim portion 65 of a hat is passed.

The brace member b , or the separate parts b^2 thereof are also U-shaped in form, as clearly shown in Figs. 4 and 5, and the ends thereof are pivoted to the free ends of the 70 parts a^2 of the top yoke-shaped portion a as shown at b^4 , and pivoted within the separate parts b^2 adjacent to the connection of said parts with the yoke-shaped portion a are spring catch or clasp devices d which 75 are adapted to fold within the U-shaped portions b^2 , as clearly shown in Fig. 4, when the separate parts of the hanger are in their folded position, and said devices d are adapted to serve as skirt, trousers or other 80 supporting means, it being understood that the transverse brace member b also serves as a skirt or trouser support.

Pivotedly mounted within one of the parts a^2 of the top yoke-shaped portion a is a 85 hook-shaped and yoke-shaped suspending device e composed of heavy wire or the like, the separate side members e^2 of which are provided with inwardly set portions as shown at e^3 , and the ends of said portions 90 are provided with parts arranged at right angles thereto, as shown at e^4 , said parts being adapted to pass through apertures in said part a^2 , as clearly shown in Figs. 1, 2 and 3, and riveted as shown at e^5 , and said 95 part a^2 is provided between the pivot of said hook-shaped suspending device e and the pivot of the separate parts a^2 at a^3 with notches or recesses a^4 into which the portions e^3 of the hook-shaped suspending device e enter when the hanger, or the separate parts thereof are in their folded position, as clearly shown in Fig. 2.

With this construction, we provide a garment hanger or supporting device which is 105 simple in construction and which may be compactly folded together, as clearly shown in Fig. 2, and it will be noted that the pivotal connection of the parts b^2 at b^3 is below the central line of said separate parts whereby the hanger a , or the parts a^2 thereof may 110 be held against inward movement in the use

thereof unless the separate parts b^2 of the brace member b be forced inwardly, or in the direction of the arrow x by hand, and it will be also noted that one of the parts b^2 is provided with an overlapping portion b^5 which limits the outward movement of said separate parts as will be readily understood.

The hat supporting device c serves also as a reinforcing and spacing means for the separate parts a^2 of the yoke-shaped portion a where they are hinged together at a^3 as will be readily understood.

Having fully described our invention, what we claim as new and desire to secure by Letters Patent, is:—

1. A garment hanger of the class described, comprising a yoke-shaped portion composed of separate parts hinged together, said separate parts being U-shaped in form in cross section, a transverse brace member composed of separate parts pivoted to the free ends of said yoke-shaped portion, said separate parts being U-shaped in form in cross section, means for reinforcing the separate parts of the yoke-shaped portion where they are hinged together, said means serving as a hat suspending device, and a suspending device pivoted to one of the separate parts of said yoke-shaped portion.

2. A garment hanger of the class described, comprising a yoke-shaped portion composed of separate parts hinged together, said separate parts being U-shaped in form

in cross section, a transverse brace member composed of separate parts pivoted to the free ends of said yoke-shaped portion, said separate parts being U-shaped in form in cross section, means for reinforcing the separate parts of the yoke-shaped portion where they are hinged together, said means serving as a hat suspending device, a suspending device pivoted to one of the separate parts of said yoke-shaped portion, and garment suspending devices pivoted to the separate parts of the brace members.

3. A garment hanger of the class described, comprising a yoke-shaped portion composed of separate parts hinged together, a transverse brace member composed of separate parts pivoted to the free ends of said yoke-shaped member, a hat suspending device pivotally suspended between the separate parts of the yoke-shaped member where they are hinged together and adapted to fold therebetween, and a suspending device mounted in connection with one of the separate parts of said yoke-shaped member.

In testimony that we claim the foregoing as our invention we have signed our names in presence of the subscribing witnesses this 20th day of July 1916.

JACOB BELASCO.
ABRAHAM SHAPIRO.
